UNITED STATES PATENT OFFICE.

ROBERT M. BELFRAGE, OF CANNONSVILLE, NEW YORK.

REEFING UPPER TOP-SAILS.

SPECIFICATION forming part of Letters Patent No. 313,279, dated March 3, 1885.

Application filed October 27, 1884. (No model.)

To all whom it may concern:

Be it known that I, ROBERT M. BELFRAGE, of Cannonsville, county of Delaware and State of New York, have invented an Improvement 5 in Reefing Upper Top-Sails; and I hereby declare the following to be a full, clear, and exact description thereof.

My invention relates to a new and useful improvement in reefing the upper top-sail, the 10 object of which is to enable the operation to be performed from the deck.

My invention consists in the novel arrangement of the upper top-sail reef-tackles, whereby the sail is adapted to be reefed to the lower 15 top-sail yard instead of to the upper one, in the arrangement of spilling-lines to spill or smother the sails, and in a false foot or ridge across the sail just above its foot, whereby 20 when the sail is reefed the false foot strengthens it, all of which I shall hereinafter fully explain.

The object of my invention is to provide a means for reefing the upper top-sail effectively and rapidly from the deck.

25 Referring to the accompanying drawings, Figure 1 is a perspective view of a mast, showing the upper top-sail and the means for reefing it. Fig. 2 is an elevation of the front of the upper top-sail.

30 A represents the deck of a vessel, and B one of its masts, which for the purpose of this description may be the mainmast.

C is the main-yard, D the lower top-sail yard, and E the upper top-sail yard.

35 F is the top-gallant yard, and G is the royal yard.

H is the upper top-sail, bent and secured to the upper top-sail yard in the usual manner, and clewed down to the lower top-sail 40 yard. Across the back of the sail, about one-third of the distance from its foot, is secured a ridge-band, I, extending longitudinally of the sail. This may be made of any suitable material, though I prefer that it should be 45 made of pliable wire. This ridge-band forms a false foot to the sail when reefed, as I shall hereinafter show.

J are the halyards, secured to the upper top-sail yard and also to the deck by the usual 50 purchase-lines j.

K are the upper top-sail reef-tackles, which below are belayed to the fife-rail L, and pass upward through the maintop and through the usual blocks outward under the lower top-sail yard, their pendants being made fast to the leech of the sail at a point below its longitudinal center, preferably at the ends of the ridge-band. The pendants of the reef-tackles I prefer to be made of wire or chain.

M are lines which I call "spilling-lines." 60 These are belayed on the deck to the fife-rail, and thence extend up and over suitable blocks at the top-mast head and down on each side to the blocks m', through which said blocks the legs m of the spilling-lines pass. 65 These legs, one on each side of the mast, consist of a single line, the ends of which pass down through guide-blocks on the upper top-sail yard, down through suitable eyes on the front of the sail, and through eyelets in said 70 sail, located just above the ridge-band I, and down through eyes O on the foot of the sail, and are secured to the lower top-sail yards.

The ordinary or usual manner of reefing the upper top-sail is as follows: The halyards are 75 let go to allow the upper top-sail yard to drop, and the reef-tackles are then pulled on to haul the sail up to the said upper top-sail yard, when said tackles are then made fast below. The men aloft go out to the outer ends of the 80 upper top-sail yard and secure the sail there by means of the usual reef-earings. These are necessary in order to hold the sail to its position, while the reef-tackles are let go in order to allow the halyards to pull the yard up again; 85 but by my invention I propose that this reefing shall be done from the deck, and for this purpose in the first place it will be observed that the pendants of the reef-tackles are not secured to the upper portion of the leech, as 90 is usual, but are secured to the lower portion about at the ends of the ridge-band. In this way the sail instead of being reefed to the upper yard is pulled down to the lower yard, and thus there is no necessity for any reef- 95 earings, for the lower top-sail yard being stationary there is no need of letting go the reef-tackles after being once made fast, because the halyards having only to do with the upper top-sail yard the reef-tackles do not prevent 100

their use. When the reef-tackles are belayed, the sail is reefed down to the lower yard and there held without the necessity of going aloft; but if such necessity should arise it can be further secured by tying the reef-points P; but ordinarily the reef-tackles are sufficient of themselves to hold the sail to its reefed position, the ridge-band then acting as a false foot for the sail and preventing it from straining and tearing. The spilling-lines by their course through and about the sail serve when taut to spill the sail when reefing, or to smother it in, so that it can be furled or reefed.

In order to reef the sail, the operation is as follows: Haul taut the spilling-lines, let go the top-sail halyards, haul out the reef-tackles and belay, tie the reef-points on the foot of the sail, if necessary, if not, hoist away on the top-sail halyards again.

Having thus described my invention, what I claim as new, and desire to secure by Letters Patent, is—

1. The upper top-sail, H, adapted to be reefed down to the lower top-sail yard, in combination with the spilling-lines M, the fall of which is on deck, their upper portions being guided by suitable blocks, and having legs *m* passing down to and traversing and interlacing the sail vertically, and secured to the

lower top-sail yard, as shown, substantially 30 as and for the purpose herein described.

2. The upper top-sail, H, in combination with the upper top-sail reef-tackles K, the pendants of which are made fast to the leech of the sail below its longitudinal or horizontal 35 center, and the spilling-lines M, having legs *m* traversing and interlacing the sail vertically, and secured to the lower top-sail yard, all arranged and operating substantially as and for the purpose herein described.

3. The upper top-sail, H, having the ridge-band or false foot I, extending horizontally across it below its longitudinal center, in combination with the upper top-sail reef-tackles K, the pendants of which are made fast to the 45 leech of the sail at or about the ends of the ridge-band, and the spilling-lines M, having legs *m* traversing and interlacing the sail vertically, and secured to the lower top-sail yard, substantially as and for the purpose herein de- 50 scribed.

In witness whereof I have hereunto set my hand.

ROBERT M. BELFRAGE.
